Fig. 4

Fig. 5

Fig. 6

FIG. 1 is a top plan view of an air brush showing my new design;

FIG. 2 is a side elevation thereof;

FIG. 3 is a front elevation thereof;

FIG. 4 is a rear elevation thereof;

FIG. 5 is a bottom plan view thereof; and

FIG. 6 is a rear perspective view thereof taken from the side opposite that shown in FIG. 2.

The fragmentary showing of containers in FIG. 2 is for illustrative purposes only.

The characteristic features of my design reside in the portions of the air brush comprising the rear half thereof.

I claim:

The ornamental design for an air brush, as shown and described.
